UNITED STATES PATENT OFFICE

2,471,565

CONTAINER AND CLOSURE THEREFOR

Gustave Glocker, Washington, D. C.; Eugenie Glocker, administratrix of said Gustave Glocker, deceased, assignor to Super-Seal Container Corporation, Washington, D. C., a corporation of Delaware

Application December 4, 1945, Serial No. 632,647

2 Claims. (Cl. 215—40)

1

The present invention relates to a closure cap for sealing the mouth of a receptacle such as a bottle, jar, or the like. The invention more specifically pertains to the structural arrangement of the peripheral portion of the cap and particularly the annular portion intermediate the relatively flat top and the skirt.

It is an object of the invention to provide a depending skirt at the periphery of the cap so shaped at the juncture thereof with the top portion as to provide a channel therearound for accommodating a sealing composition and forming an abutment surface for limiting the displacement of the sealing composition during application of closure member on the receptacle.

A still further object of the invention is to provide a closure cap of a simplified design which may be readily manufactured and at the same time to provide a reliable arrangement for hermetically sealing the pouring opening of a jar, bottle or similar container.

Other objects and features of the invention will be more apparent to those skilled in the art upon consideration of the following detailed description and the accompanying drawing wherein a closure cap assembly embodying the invention is disclosed.

In the drawing:

Fig. 1 is a plan view of a closure cap exhibiting the invention;

Fig. 2 is an enlarged sectional view of the cap taken on the line 2—2 of Fig. 1 and showing the association of the cap with a container;

Fig. 3 is a similar sectional view taken on the line 3—3 of Fig. 1; and

Fig. 4 is a fragmentary side elevational view taken from approximately the three o'clock position in Fig. 1.

The closure cap herein disclosed pertains to the type adapted to remain in sealed association with the mouth of a container by the so-called vacuum seal method. In other words, the closure cap is maintained in closed position on the container by means of a greater pressure exerted on the exterior of the cap than that present within the receptacle. This pressure differential is obtained either by partially evacuating the container or by the condensation of hot vapors within the head space of the receptacle after the closure cap is in place so as to create a rarefied atmospheric condition therein. Thus, the greater pressure on the exterior of the cap maintains the closure member in sealed relation with the neck of the receptacle.

The present invention pertains to a closure cap

2

of such a type and includes a top portion 12 which may be formed of any suitable sheet material such as metal. In the embodiment illustrated the top portion 12 is relatively flat and generally disc-shaped. The cap may be formed of a suitable metal alloy and the peripheral portion of the disc 12 is turned upwardly and flares outwardly to provide a frusto-conical shaped surface 14 as shown in Fig. 2. This wall 14 forms one leg of a bead 18 around the peripheral portion of the cap and the apex of the bead is accordingly above the plane of the disc-shaped top portion 12. The inner surface 16 of the bead provides an annular abutment surface for a sealing composition as hereinafter described.

The upward slope of the frusto-conical wall 14 terminates at 18 and thereafter is turned downwardly substantially at right angles with respect to the surface 16. The sheet material depending from the top portion of the bead 18 forms a skirt 20 which flares outwardly and downwardly to provide a substantially frusto-conical annular skirt for the cap. The skirt 20 is thus formed from an integral portion of the sheet material and it is preferably arranged substantially parallel to an exterior surface 22 of the receptacle neck as shown in Fig. 2. The lower portion of the skirt is turned inwardly and upwardly to provide a substantially U-shaped bead 24 around the lower end portion of the skirt. This bead materially reinforces the skirt portion and provides means for retaining an annular layer of sealing composition around the inner surface of the skirt.

The closure cap includes and carries a resilient and yieldable plastic composition for sealing the cap with reference to the receptacle neck shown at 25. Any suitable known compound may be employed as the sealing composition such as one containing about thirty per cent water, approximately twenty-four per cent rubber, and the remainder of material fillers and protectives. The plasticity of such a compound may be adjusted so as to provide some displacement of the material during the arrangement of a cap over the mouth of the receptacle and in response to relatively slight pressure applied axially of the container opening. The plasticity and viscosity characteristics desirable in such a sealing composition and suitable for the purposes of the present invention are known in the art and disclosed in the patent to Dewey and Crocker No. 1,765,134. It is to be appreciated, however, that other known sealing compositions may be employed for provid-

ing the hermetically sealed juncture between the closure member and the receptacle.

The sealing composition is indicated generally at 26 and is retained around the inner surface of the skirt 20 by the channel formed between the abutment surface 16 and the inturned flange 24 around the lower end of the skirt. Thus when the cap structure is arranged over the neck of a bottle or other receptacle, the somewhat plastic sealing composition engages the peripheral surface 22 and the sealing composition is displaced to provide a hermetically sealed juncture between the plastic compound and the receptacle. The abutment surface 16 limits the upward displacement of the sealing compound.

The cap structure includes means for conveniently impairing the vacuum within the head space of the receptacle so that the cap may be readily removed. This arrangement includes an opening 28 in the skirt 20 so that a pointed tool or implement may be readily introduced through the opening 28 for penetrating the sealing composition and admitting air to the interior of the container. This equalization of the pressure permits the cap to be readily removed from the neck of the receptacle. The cap structure includes a protuberance 30 in the disc-shaped top portion 12 and this raised portion 30 is in alignment with the opening 28 so that the tool may pass over the top edge 32 of the receptacle wall and completely penetrate the sealing composition.

The sealing material is somewhat plastic as hereinabove explained and the cap structure includes a tongue 34 adjacent the opening 28 for preventing the outward displacement of the plastic composition when this material is arranged within the skirt and when the cap is urged into a receptacle-closing position over the mouth of the container. The tongue 34 may be formed from an integral portion of the skirt 20 and upset slightly inwardly as shown in Fig. 3. This tongue effectively prevents the escape of the plastic material through the opening 28 and at the same time provides an arrangement whereby the vacuum breaking tool may be readily urged through the sealing composition to break the vacuum within the receptacle without the necessity of puncturing an imperforate portion of the skirt.

While the invention has been described with reference to specific structural details and with respect to particular types of material both for the cap structure and the sealing composition, it will be understood that changes may be made in all of these elements. Such modifications may be made without departing from the spirit and scope of the invention set forth in the appended claims.

I claim:

1. A package consisting of a container having a neck terminating in a mouth, a closure cap on the mouth of said container comprising, a disc-shaped top portion having a diameter substantially equal to the outer edge of the receptacle neck and adapted to rest in substantial contact with the walls defining the mouth of said recep-

tacle, an annular bead carried by the peripheral portion of the disc-shaped top portion above the plane thereof and extending outwardly about the mouth of said receptacle, an annular frusto-conical shaped skirt depending from said bead and arranged substantially at right angles to the inner opposite wall of the bead and substantially parallel to an exterior surface of the receptacle neck whereby said closure cap may be seated without substantial pressure, an inwardly directed flange carried at the lower portion of the skirt, a sealing composition flowable under elevated temperature forming an annular layer of substantially uniform thickness about the inner surface of the skirt between the flange and the bead, the inner face of said annular layer being substantially parallel to the exterior seating surface of said neck, and said opposite wall of said annular bead forming an abutment surface limiting the upward and inward displacement of the heat flowable sealing composition.

2. A package consisting of a container having a neck terminating in a mouth, a closure cap on the mouth of said container comprising, a disc-shaped top portion having a diameter at least as great as the outer edge of the receptacle neck and adapted to rest in substantial contact with the walls defining the mouth of said receptacle, an inverted V-shaped bead around the disc-shaped portion with the apex thereof above the plane of the disc-shaped top portion and extending outwardly about the mouth of said receptacle, a frusto-conical shaped skirt depending from said bead substantially at a right angle to the inner wall of the bead and substantially parallel to an exterior surface of the receptacle neck, whereby said closure cap may be seated without substantial pressure, an inturned flange around the lower end of the skirt and a sealing composition flowable under elevated temperature forming an annular layer of substantially uniform thickness around the inner surface of the skirt, the inner face of said annular layer being substantially parallel to the exterior seating surface of said neck, whereby the inner wall of said bead forms an abutment surface limiting the upward and inward displacement of the heat flowable sealing composition upon application of the cap to the mouth of the receptacle.
